CIRCULAR-KNITTING MACHINE

Application filed December 21, 1926, Serial No. 156,190, and in Great Britain December 21, 1925.

This invention comprises improvements in or relating to circular knitting machines and has particular, although not exclusive reference to double cylinder knitting machines adapted for the production of ribbed fabrics.

The object of the invention is to furnish an improved mode of and improved means for operating and controlling the relative disposition of a plurality of yarn feeds to the machine needles so as to vary the relative positions of the yarns at the time of laying same upon the needles and by so doing determine which of said yarns appears in or 15 at the front of the fabric.

Heretofore, it has been customary to effect the relative movement of the yarn feeds directly from a travelling chain having raised links or elements incorporated therein. It has been found, however, that operation from a chain in this manner does not result in a consistently accurate operation of the yarn feeds, and the improvements incorporated in the present invention function primarily to produce a more positive operation of said feeds and by so doing ensure a continuously accurate control of said feeds and consequently the production of accurate results in the fabric.

30 A feature of the present invention consists in the provision in a circular knitting machine of a cam drum or the like for controlling the relative movement and disposition of a plurality of displaceable yarn feeds in combination with another or main control drum, chain or other source which functions to render the first named drum operative or inoperative and to determine the operative and inoperative periods thereof.

40 Another feature of the invention consists in providing upon the drum which operates the yarn feeds a plurality of cam members, one of which functions through suitable intervening mechanism to change the relative 45 positions of the movable yarn feed members,

while another cam serves at predetermined intervals to return said feeds to their normal position.

A further feature resides in the provision in combination with the yarn feed operating means as above of automatically operable means for holding the yarn feed members in their displaced position prior to the return thereof to the normal position.

Another feature resides in effecting the 55 operation and control of the yarn feed control drum from the main control drum, chain or the like or cam through the intermediary of an additional rotating cam device.

Further features are included in the construction, arrangement and mode of operation hereinafter more fully described.

For the purpose of more fully describing the nature of this invention reference will 65 now be made to the accompanying drawings wherein:-

Fig. I is an elevational view of yarn feed operating and controlling mechanism in accordance with this invention.

Fig. II is an elevational view of a part of a main control drum and means associated therewith, such view forming a continuation of Fig. I.

Fig. III is a plan view of part of the mechanism shown in Figure I.

Figure IV is an elevational view looking in the direction of arrow A in Figure I.

Figure V is a detail view of cams employed in the invention.

Figure VI is a detail view of the pattern drum check wheel device.

In one method of carrying out the invention, a main control drum 1 (Fig. II), cam or other suitable device which is intermittently rotated by ratchet mechanism preferably controlled by travelling chain, has coating with its circumferential face the one end of a rod 2, hereinafter called the control rod, said rod, being caused by rises and falls on 85 90

the control drum 1 to move longitudinally in both directions. The effective length of the control rod is adjustable by nuts 3 coacting with right and left hand screw threads on the rod, which is formed in two parts. The other end of this control rod (which rod is preferably horizontal) operates upon a pivoted member 4 (Figs. I and IV) which in turn coacts with a displaceable cam follower 5 to move same into and out of contact with a cam 6 carried by a rotating cam shaft 7. When this follower 5 is in contact with the cam 6, pawl and ratchet mechanism is actuated to rotate intermittently and preferably to the extent of one tooth per revolution, a drum 8 which will be termed the pattern or plating drum.

The end of the control rod adjacent to the main drum 1 is pivotally connected to one arm of a crank lever 9 which is pivotally connected to a bracket 10 fixed to the machine frame 11, the other arm of lever 9 having a nose 9^a which coacts with the main drum 1.

The pivoted member 4 at the other end of the control rod is of forked shape and has a depending pin 4^a (Fig. IV) by which same is rotatably mounted within a suitable hole in a bar or plate 12 rigidly fixed to the machine frame, or part thereon. The control rod may be connected to said rotatable member 4 by fixing an eye portion 2^a terminating said rod on to a pin projecting up from a lateral lug 13^a on said member 4.

The cam 6 on the shaft 7 may be in the nature of an eccentric, and the arrangement is such that when the member 4 is partially rotated, which movement occurs when the crank lever 9 rises upon a cam rise 1^a on the main drum 1—the follower 5 is swung laterally from engagement with an idling part 6^a (Fig. V) of the cam on to the cam proper 6. This position is maintained so long as the lever 9 of the control rod remains upon the main drum rise 1^a, and while the follower is so positioned same operates upon the lower end of a vertically guided slidable pin or tappet 14 to reciprocate said tappet and pivotally displace a small lever 15 carrying a spring-pressed pawl 16 which is maintained in engagement with the teeth of a ratchet wheel 17 fixed to rotate with the pattern drum 8. In this way the drum 8 is intermittently rotated or racked. Preferably the tappet 14 coacts with the lever 15 through an adjustable screw element 15^a.

A suitable check wheel 18 may be installed upon this pattern or plating drum 8, said wheel having circumferential teeth or notches with which engages a spring-influenced pin or element 19, Fig. VI, for retaining the drum 8 from movement in each direction beyond definite limits at each racking motion (Fig. VI). The teeth or notches of the check wheel are of V shape, the element 19 having a correspondingly shaped point or nose. Advan-

tageously the element 19 is adjustable both longitudinally and vertically upon a flattened portion of a circular or other sectioned rod 20 extending over the pattern drum at right angles to its axis, said rod being anchored at its one end to a relatively stationary part and having connected at its other end a spring 21 which is anchored at its lower end to the frame and serves to pull the element 19 down on to the wheel 18.

On the pattern or plating drum 8 are two cams 22, 23, which will be designated the first and second cams, and upon the periphery of the first cam 22 bears an adjustable element 24^a carried by the one arm of a pivoted vertically disposed two-armed lever 24. When a rise on the said first cam 22 pivotally displaces said lever 24, the latter operates to move a second cam follower or lever 25 in to the track of a second cam 26 on the before-mentioned cam shaft 7, said follower 25 being raised by said cam 26 and acting upon a vertically guided sliding pin or tappet 27 to change the relative position of the yarn feeds.

The second cam follower 25 is preferably connected to a forked pivoted member 28 (Fig. IV) in a manner similar to that described with reference to the follower 5, a pin 28^a of the member 28 being rotatably inserted within the bar 12. The lower arm of lever 24 may be adapted to bear upon a lateral pin 28^b on the member 28 or same may be suitably connected thereto; and where the lever is not positively connected to said pin, spring means are provided for maintaining the two in engagement.

The yarn feeds 29, 30 which are of any approved type pivotally or slidably mounted, are preferably both operated upon by the upstanding arm 31 of a centrally pivoted crank lever, the lower arm 32 of said crank extending approximately horizontally and being acted upon by the aforesaid sliding pin 27, preferably through the medium of an adjustable screw element 33 carried by said arm 32.

When this arm 32 of the crank is raised to change the feeds, a catch member 34 automatically operates to move beneath said arm and retain same and the feeds 29, 30 in the placed position until the second cam 23 on the pattern or plating drum 8 operates upon a second adjustable element 35^a carried by another pivoted vertically disposed two-armed lever 35 to displace said lever on its pivot and withdraw the catch 34 from beneath the arm 32.

Preferably the lever 35 is normally retained in position with the adjustable element 35^a bearing upon the cam 23 by a spring 36 (Fig. III) which may be connected at its one end to the catch 34 and at its other end to a convenient stationary bracket or frame member.

When a rise on the cam 22 acts to displace the follower 25, said follower is moved from

an idling part 26^a on the cam shaft 7 on to the cam proper 26, the latter preferably being a half-round cam, i. e. 180°. On the withdrawal of catch 34 from the arm 32, the feeds 5 return to their normal position under spring influence.

The arms 31, 32 appertaining to the yarn feeds are conveniently connected by a part rotatably mounted within a sleeve 37, an additional arm 39 projecting horizontally from the base of the upstanding arm 31 having a spring 40 connected thereto which serves to return the feeds and associated parts after displacement.

15 It will be appreciated that by determining the sizes and disposition of the cam pieces on the cam 22 relatively to those on the cam 23 the length of the periods during which the thread feeds are maintained in either position, i. e. normal or displaced, can be readily ascertained and varied.

In the production of stockings or socks, on commencing the leg after knitting the welt or stocking top, the main control rod 2 is moved by a comparatively low cam rise 1^a on the main drum 1 so as to effect operation of the pattern or plating drum 8 and produce the required pattern in the fabric, this position of the rod 2 being maintained throughout the knitting of the leg. During the knitting of the heel and toe, a part of the main drum 1 having no cam rise coacts with the control rod 2, which latter is thereby moved to displace the follower 5 from the cam 6 serving to operate the pattern or plating drum racking means, and said drum is retained stationary.

It will be appreciated that if the catch 34 is prevented from passing beneath the arm 32 when the latter is raised by the cam 26 and the feeds changed, said arm 32 will be raised and lowered and the feeds alternately displaced and returned to their normal position every half revolution of the cam shaft 7, and as the shaft 7 rotates once to every revolution of the machine cylinder, the feeds will be changed at the completion of each half course.

To accomplish this a short comparatively high cam piece 1^b on the main control drum 1 operates to move the control rod 2 further than when operated from the cam piece 1^a, and in so doing cause the two-armed lever 35 to be displaced to an extent sufficient to withdraw the catch 34 and maintain same in a position clear of the arm 32 of the yarn feed.

To enable this to be effected, the end of the lower arm of the lever 35 accommodates and is movable upon a spindle 41 which projects laterally from an arm 42 suitably secured to an extension of the pin 4^a of the rotatable fork member 4 appertaining to the follower 5 (Fig. IV). A nut 43 adjustable upon the spindle 41 is normally spaced from the lever

35, and when the control rod 2 and follower 5 are moved by the smaller cam piece 1^a, said nut bears against but does not displace the lever. When, however, the larger cam piece 1^b comes into action, the follower 5 is pivotally displaced to a larger extent and the nut 43 pulls in the lever 35 to hold the catch 34 clear of the arm 32.

In knitting the foot, after producing the heel a predetermined number of courses are knitted wherein no rise occurs on the first cam 22 on the pattern or plating drum 8 and the cam follower 25 operating the vertically sliding pin 27 to move the yarn feeds is held idle. These courses are followed by a predetermined number of courses wherein a rise on the first cam 22 moves second cam follower 25 to operate said sliding pin coacting with the yarn feed change member. The courses wherein the sliding pin 27 is not operated alternate with those wherein same is operated. The cam shaft 7 actuating the cam followers makes one revolution per course, and the rise thereon coacting with the sliding pin is as before stated around 180°, so that during one half of a revolution the sliding pin is raised to alter or reverse the position of the threads in the foot upper, and during the second half of the revolution said pin is lowered to produce normal pattern or knitting in the foot sole.

The main control drum preferably rotates to the extent of one revolution during the production of a complete stocking or sock.

The parts 5^a, 25^a of the two cam followers 5 and 25 which coact with the cams are preferably pivotally mounted so as to be capable of a lateral displacement in one direction, i. e. away from the respective cams 6 and 26, thus enabling the main drum to be racked by hand without fear of damaging the followers or cams.

If desired, the half-round cam 26 may be formed in two halves, i. e. the cam is divided in the direction of its length, said two halves being relatively adjustable so as to ensure the exact required length of cam being obtained.

As before stated, any suitable yarn feeds or guides may be employed. In the drawings the one feed 29 is in the form of a small bore tube having a funnel-shaped mouth said feed being carried by a pivoted arm 44. This arm 44 is swung on its pivot by the displacement of the upstanding arm 31 through the medium of a suitably guided member 45 which coacts with a pin 44^a on the feed arm 44. Simultaneously with the displacement of feed arm 44 a cam piece on the upstanding arm 31 coacts with a second feed arm 46 pivoted at 46^a to swing in a horizontal plane, said arm 46 carrying a small yarn feed 30 at its free end.

Claims:

1. In a circular knitting machine, a plu- 130

rality of relatively displaceable yarn feeds, a rotatable drum, a cam on said drum functioning relatively to displace the yarn feeds, a second cam on said drum functioning to determine the return movement of said yarn feeds, automatically operated means for holding the yarn feeds in their displaced position prior to their return to the normal position, and a main control means controlling the operation of the first-named drum.

2. In a circular knitting machine, a plurality of displaceable yarn feeds, a cam drum functioning as a pattern drum for controlling the relative movement and disposition of said feeds, a main control means, a third rotary cam device, racking mechanism for the pattern drum, a displaceable cam follower operated at predetermined intervals from the main control drum to coact with a cam on the third cam device and bring into operation the pattern drum racking device, a second displaceable cam follower coacting with said third cam device, and lever mechanism operable from the pattern drum to cause the said second cam follower to coact with a second cam on the said third cam device and in so doing effect a change in the relative positions of a plurality of the yarn feeds.

3. In a circular knitting machine, a plurality of relatively displaceable yarn feeds, a cam drum functioning as a pattern drum for controlling the movement of said yarn feeds, a main control means for determining the operative and inoperative periods of said pattern drum, a third rotary cam device operating intermediate of the main control means and the pattern drum, racking mechanism for the pattern drum, a cam on the pattern drum, lever mechanism operated by the said cam of the pattern drum, a cam appertaining to the third rotary cam device, a cam follower moved by the said lever mechanism into position to be operated by the said cam of the third rotary device, means for causing displacement of the yarn guides, operated by said cam follower and a second cam on the pattern drum serving to determine the periods during which said feeds remain displaced from their normal position.

4. In a circular knitting machine, a plurality of relatively displaceable yarn feeds, a pattern cam drum controlling displacement of said feeds, a main control means for determining the operative and inoperative periods of the pattern drum, the control of the said pattern drum from said main control being effected through the intermediary of a third rotary cam device having two cam members thereon, pawl and ratchet mechanism for intermittently racking the pattern drum, a cam follower operated from the main control and adapted to coact with one of the cams on the third cam device for bringing into operation said racking mechanism, a cam member on the pattern drum operating to

move through lever mechanism a second cam follower on to the second cam member on the third rotary cam device and said follower when so moved effecting relative displacement of the yarn feeds through the medium of a sliding tappet, a stop member automatically operated by spring means to coact with an arm of the yarn feed mechanism and retain the feeds in the displaced position, and a second cam on the pattern drum functioning to displace said stop and permit return of the feeds to their normal position.
